US0D1016237S

(12) **United States Design Patent** (10) **Patent No.:** **US D1,016,237 S**
(45) **Date of Patent:** **** Feb. 27, 2024**

(54) **FAUCET**

(71) Applicant: **Jing Lyu**, Shenzhen (CN)

(72) Inventor: **Jing Lyu**, Shenzhen (CN)

(**) Term: **15 Years**

(21) Appl. No.: **29/902,043**

(22) Filed: **Sep. 8, 2023**

(30) **Foreign Application Priority Data**

Aug. 11, 2023 (CN) 202330514641.9

(51) **LOC (14) Cl.** **23-01**

(52) **U.S. Cl.**

USPC **D23/238**

(58) **Field of Classification Search**

USPC D23/238-244, 252, 254-255, 257, 499;

D7/398

CPC F16K 31/602; F16K 31/605; F16K 31/607;

E03C 1/0412

(57) **CLAIM**

The ornamental design for a faucet, as shown and described.

DESCRIPTION

FIG. 1 is a front perspective view of a faucet showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the faucet that form no part of the claimed design.

1 Claim, 7 Drawing Sheets
